UNITED STATES PATENT OFFICE.

DAVID M. IRELAND, OF DETROIT, MICHIGAN, ASSIGNOR TO WILLIAM G. HOWARD AND FRED E. LEE, EXECUTORS OF P. D. BECKWITH, DECEASED.

DESIGN FOR AN ORNAMENTAL TOP FOR STOVES.

SPECIFICATION forming part of Design No. 21,501, dated April 26, 1892.

Application filed December 21, 1891. Serial No. 415,799. Term of patent 14 years.

To all whom it may concern:

Be it known that I, DAVID M. IRELAND, a citizen of the United States, residing at Detroit, in the county of Wayne and State of Michigan, have invented and produced a new and original Design for the Tops of Stoves; and I do declare the following to be a full, clear, and exact description of the invention, such as will enable others skilled in the art to which it appertains to make and use the same, reference being had to the accompanying drawing, and to the letters of reference marked thereon, which forms a part of this specification.

15 This invention relates to a new and original design for an ornament for the tops of stoves; and it consists in the formation and arrangement of parts, as hereinafter set forth, to produce the effect illustrated in the accompanying drawing, which shows an elevation of my design.

Referring to the letters of reference, A designates an annular base having the vertical rim *a*, above which rises the convexed surface *b*, that merges into the conical center *c*, which culminates in a vertical stem *d*, having annular bands of molding. Mounted on said stem

is a large sphere *B*, upon which is supported the annular grooved base *e* of the pinnacle *C*, which carries the small fluted globe *D*, having the pinnated ornament *E* at the top.

F designates four semicircular brackets located on opposite faces of the sphere *B*, extending some distance therefrom and concentric therewith. The upper ends of said brackets are attached to the pinnacle *C* and their lower end portions to the stem *d* of the base, from which point the scrolled ends *f* of said brackets depend, the face of said brackets being provided with some ornamental configuration, as shown, and the whole presenting a symmetrical and pleasing design.

Having thus fully set forth my invention, what I claim as new, and desire to secure by Letters Patent, is—

The design for the top of a stove, substantially as herein shown and described.

In testimony whereof I affix my signature in presence of two witnesses.

DAVID M. IRELAND.
